JACOB REESE, OF PITTSBURG, PENNSYLVANIA.

Letters Patent No. 82,876, dated October 6, 1868; antedated October 2, 1868.

IMPROVED MACHINE FOR WORKING IRON.

The Schedule referred to in these Letters Patent and making part of the same.

TO ALL WHOM IT MAY CONCERN:

Be it known that I, JACOB REESE, of the city of Pittsburg, in the county of Allegheny, and State of Pennsylvania, have invented a new and useful Improvement in Machine for Working Iron; and I do hereby declare the following to be a full, clear, and exact description thereof.

In the ordinary mode of working wrought iron, the balls of heated metal, just as they come from the boiling or puddling-furnace, are placed in a squeezer, and rolled into blooms of six or seven inches diameter, and of from fifteen to eighteen inches in length. These blooms are then rolled, between "muck"-rolls, into what are called muck-bars. Such rolls require numerous grooves, of different sizes, in order to reduce the bars to the width and thickness required, which fact renders the muck-rolls very expensive; and, as the bars must be transferred from one side of the rolls to the other during the process of rolling, a considerable amount of skilled labor is required, with a corresponding increase of expense. The cost of rolling muck-bars is found to be about one dollar per ton. To save all or the greater part of the cost and labor required by this process, as well as to obviate other objections hereinafter to be noticed, I have devised a machine, automatic in its operation, for working the balls of iron produced in a puddling or boiling-furnace by compression, so as to form muck-bars without the intermediate process of the use of the squeezer, and without the use of rollers, or, if the use of the squeezer is preferred, to reduce blooms to bars by means of compression, as distinguished from the process of rolling.

The nature of my invention consists in the application, for the purpose just named, of compressing-dies of such shape, and so combined with and operated by cams, as that the balls or blooms, when fed into the machine, shall be drawn through, and, at the same time, thoroughly worked, as well as reduced to the required size and shape, and then discharged from the machine in the form of a bar, the length of which is limited, not by the size of any single ball, but by the number of balls or quantity of iron fed into the machine.

To enable others skilled in the art to make and use my invention, I will proceed to describe its construction and mode of operation, referring, for that purpose, to the accompanying drawings, making a part of this specification, in which—

Figure 1 represents a top view of my machine.

Figure 2 is a vertical front elevation.

Figure 3 is a vertical rear elevation.

Figure 4 is a vertical cross-section through the line $x x$, fig. 1; and

Figure 5 is a face view of the guide used in each of the side dies.

Figures 6 to 13 are designed to represent the action of the machine in uniting into one continuous bar successive balls of iron.

Like letters of reference, in the different figures, indicate like parts.

A is a housing, of any convenient construction, resting on a bed or foundation, B. $a a, a' a'$, the relative positions of which are shown in fig. 4, are similar shafts, carrying, nearly or exactly midway between their ends, the eccentrics $c c, c' c'$, respectively, and being furnished, near their ends, with the lateral cams $e e, e' e'$.

D and D' are two reciprocating and compressing die-blocks or jaws, so shaped and so hung on the eccentrics $c c'$, that the lower face of the one, D, and the upper face of the other, D', shall approach each other, toward the rear of the machine, and so that they shall, when operated, move in a vertical direction, and alternately toward and from each other.

E and E' are two non-reciprocating compressing die-blocks or cheek-plates, with inner faces nearly or quite parallel to each other, and so adjusted on the shafts $a a'$ that they shall be made to approach each other by the action of the lateral cams $e e'$, but have no longitudinal or reciprocating motion, as the jaws D D' have. I therefore distinguish the cheek-plates E E' as "non-reciprocating compressing die-blocks," and the jaws D D' as "reciprocating and compressing die-blocks."

Wedges b are attached to the vertically-moving jaws D D' in such a way that, as the latter recede from each other to the position shown in fig. 2, the cheek-plates E E' may approach each other, under the action of

the lateral cams $e e'$, as already stated, and so also that, when the jaws D D' approach each other, under the action of the eccentrics $c c'$, the wedges b will cause the cheek-plates E E' to recede from each other to the position shown in rear view, in fig. 3. Thus the vertically-moving jaws D D' close when the cheek-plates E E' open, and *vice versa*.

The motion required to operate the devices named may be communicated through a pulley or band-wheel, m , shaft m' , and any desirable arrangement of gear-wheels, n , or in other known or convenient manner.

l is a fly-wheel of the usual construction.

To the front of the machine is attached an inclined feeding-trough or fore-plate, C, on which to place the balls or blooms to be fed into the machine, and so situated that the balls or blooms placed thereon will come opposite to the opening between the dies.

The cams which produce the lateral motion of the cheek-plates E E' are shaped like the crabs ordinarily used for throwing shafting in and out of gear, being circular disks placed concentrically on the shafts $a a'$, having inclined faces, like the thread of a screw, but facing in opposite directions, and terminating in a shoulder or step, s , the depth of which is equal to the throw of the die. These crabs are operated in a direction the reverse of their use for gearing, so that, instead of the shoulders $s s$ interfering, and causing them to operate as a clutch, they merely serve as cams, to produce a reciprocating motion.

The amount of motion to be given to the jaws D D' is regulated by the amount of the eccentricity of the circular cams $c c'$, on their respective shafts $a a'$.

The cheek-plates E E' are grooved longitudinally on their inner faces, so as to receive and hold, by a dovetail joint, the removable dies f , which have each a projecting face, f' , tapering gradually in breadth from front to rear, as shown in fig. 5, its breadth, at any one point, being at least equal to the distance between the jaws D D' at that point at the moment of bite.

The devices described being in the position shown in fig. 2, a puddle-ball or bloom, as the case may be, is laid on the fore-plate C, at the front aperture g , between the dies. Then, by the proper motions, communicated through the gearing n , the eccentrics $c c'$ throw the jaws D D' first forward, as shown in fig. 1, and then toward each other, as shown in fig. 4, giving to them a reciprocating as well as compressing action, whereby they will grip the ball or bloom by its forward end, and compress it somewhat, and, with their backward motion, as produced by the further revolution of the eccentrics $c c'$, will draw the ball or bloom in between the cheek-plates E E', which have a non-reciprocating compressing action, which, in the meantime, have been separated by the wedges b , as already described. Then, as the jaws D D' separate, and lose their hold on the ball or bloom, and move forward for a new bite, the cheek-plates E E', being actuated by the lateral cams $e e'$, will move towards each other, seize the ball or bloom, compress it laterally, if need be, between the projecting faces f' of the dies f , and prevent its moving backwards, since the vertical dies move in that direction to take hold of the mass of iron at a point when their bite is narrower. The upper jaw D and lower jaw D' then, in the same manner and by a repetition of the same motions, take a new grip on the ball or bloom, compress it still more, carry it forward as the bite of the dies f in the cheek-plates E E' is loosened, and so on alternately till the ball or bloom passes out at the rear of the machine through the smaller aperture g' in a muck-bar shape, and of the desired width and thickness. If a bloom is passed through the machine, it is compressed and worked with a narrower bite, at each stroke, until it is reduced to the shape of a long bar. If a puddle-bar is put into the machine, it is similarly squeezed, compressed, and worked; the operation of the machine dispensing with the necessity of using a squeezer to remove the cinder and form a bloom, because the mass of iron is kneaded and worked in a manner unlike that of the operation of either squeezing or rolling, a feature which is peculiar to my machine and especially adapted to the purpose. A continuous muck-bar may be formed by my machine from separate balls of iron, inserted one after the other, the pieces being united together in the machine. This union of the separate balls is effected by the peculiar action of the vertical and side dies, because, although the side dies hold the mass of iron in place and prevent its being carried backwards by the retrogression of the vertical dies, yet, when the vertical dies squeeze the iron, they reduce it in thickness, and the excess of iron is forced backwards, owing to the space between the vertical dies reducing in size from rear to front, as shown in fig. 5. By this means the iron thus forced backwards meets the second ball of iron, which is inserted immediately after the first one, and the two masses are united; so a third ball may be introduced, and a fourth, and so on until the muck-bar is produced of any desired length.

The action of my machine upon the masses of iron subjected to its influence differs materially from that of either rolls or hammers, this difference resulting from the peculiar nature of the operation. Iron, whether worked by rolling or hammering, is more fibrous on the surface than at or near the centre of the mass, and it is well known to the trade that it is found impossible, by the ordinary modes of working iron, to make large masses of iron as solid and fibrous at the centre as at the surface.

In rolling iron the article is greatest at the surface of the mass, and iron which at first was granular in texture is drawn out in one direction, but more on the surface than elsewhere, the drawing action decreasing towards the centre, and as the rolls are set at a fixed distance apart, and have only a small bite on the metal, they have very little squeezing action, but draw the iron from the surface, leaving the centre very much in the same granular condition as when it entered the rolls.

The effect of hammering is different from that of rolling. The faces of the hammers are flat and usually parallel. If a round ball of iron is placed under a hammer, the effect is to separate the edges, so that a small globular piece would be flattened and assume the shape of a star. Hammering, therefore, while it condenses the iron, serves to destroy the fibre and make its granular.

My machine obviates the difficulties and objections both to hammering and rolling, as it works the whole mass from centre to circumference simultaneously, and draws it out so as greatly to increase its fibrous quality.

In figs. 6 to 13, the effect produced by my machine in drawing the fibre of the iron, and uniting and welding together masses or balls inserted successively into the machine, is exhibited by the different coloring, the light portions representing one piece of iron and the darker portions representing the other.

Figs. 6 and 8 represent the effect of my machine in shaping and uniting two balls of iron, one of which is inserted after the other has been acted upon for about five or six revolutions of the machine. The machine forms the first ball into a wedge-shaped mass, but gradually the rear end also becomes pushed backwards and elongated, until it meets and is forced into the body of the second ball, which has now been inserted. Thus the iron of one piece is lapped over the other on top and bottom, and also at the sides, forming the most perfect scarring and welding that can possibly be obtained.

It is not necessary to illustrate the various changes produced on the successive masses of iron. As the mass passes out at the forward end of the machine, it assumes the flat, even surface shown in fig. 10, and a bar made from six successive balls, inserted into the machine at short intervals, is united and welded together, as shown in fig. 11.

These successive balls are not required to touch each other when inserted into the machine. All that is necessary is to keep the iron fed in so fast, that the iron which is in advance may meet the iron which succeeds it by the advance of the latter and the retrocession of the former, as before explained.

I have ascertained, by actual experiment, that by my machine, in a bar of only half inch wide, the pieces are united by a four-tongued lap-weld of over two inches long.

The advantages attending this mode of working puddle-balls or reducing blooms to muck-bars, are numerous:

First, the iron is acted on only by a compressing force, which operates at every point, nearly at right angles to the surface of the bloom. Hence the bar produced has greater solidity than when "drawn," as it must be in the process of rolling, and has sound, smooth, uniform edges, which feature itself is a great saving, as the rough, ragged, or irregular edges of rolled muck-bars are a cause of waste in the heating-furnace, and are reduced to smooth, sound edges in the further rolling only with great difficulty and waste of material.

Second, the cost of labor in passing the blooms through the muck-rolls, one dollar per ton, as above stated, is almost entirely saved, besides the labor and cost of passing the puddle-ball through the squeezers, since my machine is automatic in its operation, feeds itself after the bloom is placed in position, and discharges the complete bar.

Third, the great rapidity with which it performs its work. Thus, at every revolution of the shafts $a a'$, the dies compress the iron and carry it forward from one to three inches, more or less, according to the amount of throw which they receive. With a throw of from three to six inches at each revolution, and a speed of one hundred revolutions per minute, an amount of motion which I find perfectly practicable, my machine will turn out from twenty-five to fifty feet of muck-bar per minute, which is several times the average capacity of a good pair of muck-rolls.

Fourth, in rolling, the iron is apt to follow the roll and form collars around it, which, becoming welded as the roll revolves, are removed only after considerable labor and great loss of time, and often with the loss of the puddling, which is done or being done when the work is thus interrupted. To prevent the iron from following the roll, the guides are not a complete remedy, as they speedily become blunt from constant use and frequent heating; but with my machine this difficulty is wholly obviated. There is no rotary motion by which a collar can be formed, and the machine is free from all tendency to clog or be otherwise obstructed in its operation.

Fifth, a greatly-reduced first cost of the necessary machinery, since, in the ordinary process, rolls, with different arrangements of grooves, are required to produce muck-bars of the various widths required. Such rolls, especially if, as is usually the case, a number are required, involve a considerable outlay. One compressing-machine, provided with a proper assortment of dies, f , as hereinafter to be described, is much less costly, as well as far more efficient and more durable, and is amply sufficient to meet the demands of a single mill. The dies f may be made thicker or thinner at pleasure, so as to lessen or increase correspondingly the width of the muck-bar produced, and the faces, f' , may stand out more or less prominently at pleasure. In like manner the vertically-moving dies or jaws may be provided with removable faces or die-plates, which, in both cases, may be easily renewed, when broken or worn out, with but slight expense, little delay, and no injury to the other parts of the machine.

Sixth, all bars rolled have fins thrown up on their upper edges, to remove which the roller has to turn his bar frequently; but in my machine the dies are wider than the required bar, so that a fin cannot be formed. In this way trouble and labor are saved, and a better edge is secured to the bar produced.

If it be desirable, the cheek-plates $E E'$ may also have a forward motion similar to that of the vertically-moving jaws $D D'$, or the latter may have only a vertical or compressing motion, and the forward or feeding motion be communicated by the cheek-plates $E E'$. The eccentrics and cams should, in any such case, be so arranged as to secure the motions desired.

I do not confine myself to any particular arrangement of cams and eccentrics, or to any particular mode of operating them, though practically I prefer the arrangement of devices and the motions above set forth. Of the dies which only compress the iron, one may be stationary, if so preferred.

The shape of the working faces of the dies may assume different modifications. They may be flat, concave, convex, half round, oval, or of such other shape or shapes as may be desired, in connection with the work described. I thus adapt my machine to the making not only of muck-bars, but also of other heavy articles of slab or bar iron, of either regular or irregular shape, such as heretofore have been produced only by rolling or hammering.

Armor-plates for ships, and other heavy sheeting-plates or slabs, may be thus made. Also rails, girders, and other iron of irregular shape in cross-section may thus be made to great advantage, as the dies may readily be so made as to swage up or down any projections that may be required. This, in the ordinary process of manufacture, can be done only by hammering or passing the bar between rolls edgewise, either of which ways is attended with a loss of time, labor, and expense. One of my machines, fitted with the proper dies, will produce, by its own automatic motion, plate, slab, rail, or bar iron of almost any desirable size or shape.

The shape of the different parts of my machine is such, that each may be made of any required degree of solidity, so that the danger of breakage and of loss by wear and tear is reduced to a minimum.

What I claim as my invention, and desire to secure by Letters Patent, is—

1. The combination of a pair of reciprocating and compressing die-blocks or jaws with one or a pair of non-reciprocating compressing die-blocks or cheek-plates, acting perpendicularly thereto and alternately therewith, substantially as described.

2. An arrangement of mechanism for imparting to one or both of a pair of compressing die-blocks a reciprocating movement simultaneously or alternately with a movement of approach toward or recession from each other, substantially as described.

3. In combination with one or more compressing die-blocks, a pair of reciprocating and compressing die-blocks, the coacting-faces of which are, in their normal condition, more widely separated from one another at the point where the metal is introduced between them than at the point where the metal is extruded from them, substantially as described.

4. In combination with one or more compressing die-blocks, a pair of reciprocating compressing die-blocks, the coacting-surfaces of which, one or both, are curved, substantially as described, for the purpose, in part, of permitting and aiding to produce a more or less retrograde or backward movement of the metal while the same is being acted on, alternating with the general forward movement of the same, substantially as hereinbefore set forth.

5. In combination with a pair of reciprocating and compressing die-blocks, operating substantially in the manner described, an inclined feeding-trough, for guiding and facilitating the forward movement of the bloom or puddle-ball to and between said die-blocks, substantially as herein described.

6. As a whole, the improved machine, consisting of the several parts, constructed and combined substantially as and for the purpose described.

In testimony whereof I, the said JACOB REESE, have hereunto set my hand.

JACOB REESE.
